CONDITION-RESPONSIVE ELECTRICAL CONTROL DEVICE

Rutger B. Colt and Thomas K. Kjellman, Baltimore, Md., assignors to Bendix Aviation Corporation, Baltimore, Md., a corporation of Delaware

Application April 18, 1957, Serial No. 653,556

2 Claims. (Cl. 338—41)

This invention relates to an electrical control device for varying the resistance of an electric circuit as a function of changes in some condition or parameter, such as altitude, manifold pressure and the like.

In many installations involving electrical control circuits, cost and space requirements render it necessary to utilize control units which are relatively small and extremely simple in construction while at the same time the unit must perform its necessary function accurately over long periods of use; and an object of the present invention is to provide a condition-responsive control or regulating device which will meet these requirements.

Another object is to provide a highly sensitive, compact pressure-responsive electrical control device in the nature of a combined rheostat or potentiometer and pressure-responsive capsule in which the capsule acts directly on a contact arm, which in turn rocks or rolls on a resistance-varying element with a minimum of applied force and a controllable amount of friction.

Another object is to provide an electrical control device of the pressure-responsive type in which the change in resistance for a given change in pressure is dependably uniform over the entire range of the device and may be linear or have a predetermined degree of non-linearity, as desired.

A further object is to provide a combined pressure-responsive capsule and electrical resistor assembly of the rocker type which is simple yet accurate and capable of easy adjustment.

The foregoing and other objects and advantages will become apparent in view of the following description taken in conjunction with the drawings, wherein:

Figure 1 is a top plan view of a pressure-responsive control device in accordance with the invention;

Figure 2 is a view in section taken on the line 2—2, Fig. 1, but with the top of the case and the pressure-responsive capsule broken away to expose the resistor assembly therebelow;

Figure 3 is a view in edge or side elevation of the device of Figures 1 and 2, with parts broken away; and

Figure 4 is a detailed perspective view of the resistor assembly and the housing or case in which it is mounted.

Referring to the drawings in detail, a deeply-dished outer casing or housing is generally indicated at 10, which in practice is made of relatively thin-gauge sheet metal, preferably aluminum, to promote lightness in weight. The top wall of the housing is contoured to receive a pressure-responsive capsule 11, which is made up of a pair of opposed diaphragms joined at their meeting edges, providing a peripheral flange 11'. The top wall of the capsule, or the upper diaphragm, has secured thereto a mounting stud 12, which is threaded through the top wall of the casing and has applied thereto a lock nut 13, by means of which the position of the diaphragm may be adjusted vertically within the casing. The bottom of the capsule, or the lower diaphragm, has projecting downwardly therefrom a pointed or tapered contact member 14, which bears against a contact area 14', formed on a

contact arm 15 of conductive material, which has an arcuate contour longitudinally thereof and is also arcuate or channel-shaped in transverse cross-section, for a purpose to be explained in the description of operation. It will be noted that the contact area 14' lies in a plane normal to the vertical line of thrust of the pointed contact member 14. At its one end the arm 15 is provided with a pair of parallel pivoting or hinge lugs 15', through which a pivot pin 16 projects and by means of which the said lever is pivotally mounted on the upwardly-projecting end portion 17' of a leaf spring 17, the opposite extremity of said spring slanting upwardly and terminating in a curved contact tip or end 18, which bears against a small pivotally-mounted hollow resistor rod 19 carrying a resistor 19', which in the example shown is in the form of closely-spaced resistance wire wound on the free extremity of said rod. The parts 15, 17 and 19 comprise an assembly which is mounted within a cavity 20, formed in an inner case 21, the latter in practice being made of thermosetting plastic or similar material. The cavity 20 terminates at one end (the left-hand end as viewed in Fig. 2) in a recess 22, in which the one end of the resistance rod 19 is situated and pivotally anchored by means of a pin 23, which is projected through the opposed walls of the case at this point. The spring 17 is anchored to the base of the case 21 as at 24.

An adjusting screw 25 is threaded through the assembly-supporting case 21 and abuts the upwardly projecting arm 17' of the spring 17, to which the lever 15 is pivotally connected.

The case 21, which supports the resistor assembly, telescopes within the inverted cup-shaped outer casing 10 and is held in place therein by means of screws 26.

A pair of terminals 28 and 29 are fixed to the case 21, the terminal 28 connecting with the one end of the resistance wire 19' by means of a wire 30, while the terminal 29 connects with the one end of the arm 15 by means of a wire 31. Insulated lead wires 32 and 33 connect with the terminals 28 and 29 and are adapted to be connected into the electrical circuit to be controlled. A third wire 34 connects with the end of the resistor 19' opposite that to which the wire 30 is connected and is brought out through the hollow rod 19 and attached to a terminal 35. In the event the control device is to be used as a rheostat, terminals 28 and 29 only are connected in circuit, whereas if it is to be used as a potentiometer, terminal 35 is also connected into the circuit to be controlled in a manner well known to those having a layman's knowledge of the electrical art.

Operation

In practice, the device shown herein is used to vary the resistance of an electrical circuit as a function of changes in altitude, the said circuit being part of a direct injection system for controlling the flow of fuel to the internal combustion engine of a motor vehicle. The range of control extends from ground level to a height or altitude of say 15,000 feet. In the position of the parts as shown in Fig. 2 of the drawings, the contact arm 15 is in its high-pressure position with respect to the resistor 19', this being the ground level or near ground level position. As altitude is gained, the capsule expands and rocks the arm 15 in a counter-clockwise direction on the wire-wound resistor 19' carried by the rod 19, the transversely-arcuate or channel-shaped contour of the arm 15 and the rounded contour of the resistor causing the arm and resistor to mate and "track" one another and effect a uniform contact action for each increment of movement of the capsule 11. The free floating mounting of these elements facilitates this tracking action. That portion of the leaf spring which urges the rod 19 and its resistor 19' upwardly against the arm 15 need have only sufficient

force to insure a firm contact. Since the response of the capsule may be in minute increments over the range of altitude through which the vehicle travels, it is important that the resistor assembly respond to each such incremental change; and this is what happens with the type of assembly shown.

In the form of the device shown, it can be assumed that there is just enough friction developed between the contact surfaces of the arm 15 and the resistor 19' to ensure automatic cleaning, or prevent the build-up of an insulating film on these surfaces. Ordinarily, the amount of friction developed for this purpose produces no appreciable wear.

The response of the device may be made linear or non-linear, as desired. There are a number of ways in which linearity may be controlled. For example, the capsule 11 may be designed in a manner such as to have a linear response to some function of pressure; the arm 15 may be contoured with a varying radius; the contact area 14' may have a varied contour; or the resistance coil 19' may be wound in a manner such that the rate of resistance change per length varies. Thus the windings may be variably spaced along the length of the coil, for example, further apart in the center than at opposite ends, or vice versa.

To "range" the device (set the effective altitude correction), the screw 25 is adjusted inwardly or outwardly with respect to the upwardly projecting portion of the spring 17, which in turn repositions the arm 15 with respect to the pointed contact member 14 and varies the throw of the said arm. The length of the contact area 14' on the arm 15 is such as to cover the full range of adjustment, so that the effective throw or correction travel of the capsule and the preset relationship of the contact arm 15 and resistor 19' remains undisturbed.

The entire assembly is light in weight, compact and easily fabricated by ordinary production personnel.

What is claimed is:

1. Means for varying the resistance in an electrical circuit in response to changes in a condition comprising: a condition-responsive element and a housing therefor, said element having a part anchored to said housing and a part free to move in response to changes in such condition, an assembly-supporting case connected to said housing, a pointed contact member projecting from said movable part of said element, an elongated rod-shaped resistor and a support therefor pivotally mounted at one end only in said assembly case adjacent said element, a leaf spring anchored at an intermediate point to said assembly case and having a portion biased in a direction to engage said resistor support, an electrical contact arm of arcuate contour longitudinally thereof and of substantially channel-shape in cross section having its one end pivotally connected to the opposite end of said spring,

5 the extremity of said arm opposite its pivoted end projecting free for direct contact with said resistor, said spring urging said resistor against said arm and said arm toward said contact member, movement of the movable part of said element in response to changes in said condition acting through said contact member to cause the said arm to rockingly traverse said resistor, said resistor engaging in the channel of said arm whereby the resistor and arm are caused to accurately track one another during the traversing action, and means connecting said resistor and arm in said circuit.

10 2. Means for varying the resistance in an electrical circuit in response to changes in a condition comprising: a condition-responsive element and a housing therefor, 15 said element having a part anchored to said housing and a part free to move in response to changes in such condition, a contact member projecting from the movable part of said element, an elongated resistor, an elongated rod-shaped support for said resistor pivotally mounted at one end only adjacent said element, a contact arm having an arcuate contacting surface pivotally mounted at one end only and having its opposite end projecting free with said surface engaging said resistor, said arm and said resistor being contoured in a manner such as to 20 mate or interengage one with the other, an assembly case connected to said housing and providing a mounting for said resistor and arm, a leaf spring anchored at an intermediate point to said assembly case and having a portion biased in a direction to resiliently urge said resistor against said arm and the latter toward said contact member and another portion serving as a mount for said arm, movement of the movable part of said element in response to changes in such condition acting through said contact member to cause the arm to rockingly traverse said resistor, means for connecting said resistor and said arm in said circuit, an adjusting screw threaded through said assembly case into abutting engagement with the arm-mounting portion of said spring whereby the position of said arm with respect to the longitudinal axis of said resistor is rendered adjustable, said arm being provided with a contact surface for engagement with said contact member lying in a plane substantially normal to the direction of movement of said contact member.
